UNITED STATES PATENT OFFICE.

WILLIAM LEWIS EVANS, JR., OF WASHINGTON, INDIANA.

HINGE.

1,407,739.

Specification of Letters Patent. Patented Feb. 28, 1922.

Application filed February 24, 1921. Serial No. 447,417.

To all whom it may concern:

Be it known that I, WILLIAM L. EVANS, Jr., a citizen of the United States, residing at Washington, in the county of Daviess 5 and State of Indiana, have invented a new and useful Hinge, of which the following is a specification.

This invention relates to hinges of the multiple pivot type, in which are combined 10 with a jamb plate and a door plate, a pair of arms, the opposite ends of which are pivoted, respectively, to the said plates in such relation to each other that they always assume a non-parallel position.

15 The invention is generally an improvement upon the hinge shown, described and claimed in my Patent, No. 1,367,954, dated February 8, 1921, but is more specifically an improvement on the construction of hinge 20 shown, described and claimed in my copending application, Serial No. 346,455, filed Dec. 22, 1919.

In said application, I have shown the jamb plate made angular in form, having at 25 opposite ends vertical holes or sockets, which, when the jamb plate is applied to the door jamb, disposes the said holes or sockets respectively inside and outside the entrance or opening closed by the door, in different vertical planes. Associated with the angular jamb plate, is a door plate rigidly mounted 30 on the door, and also having a pair of holes or sockets. The holes or sockets in the jamb plate and door plate are adapted to loosely 35 receive, respectively, the downturned and upturned ends of a pair of swinging arms, said arms being removable from the jamb plate and door plate at will.

In said construction, considerable mechanical skill is necessary in properly mounting 40 the door and jamb plates in order to receive the ends of the swinging arms, and cause them to properly function, and, moreover, there are certain limitations imposed 45 on such construction which prevent it from being used for general purposes.

To construct a hinge which is more easily installed and adapted to a wider range of usefulness, I have connected the jamb plate 50 and the door plate to the ends of the swinging arms, so that the four elements constitute a single unitary structure. I have made the arms out of two plates of flat metal, and have formed the pivotal connections between the arms and the door and

60 jamb plates of interlocking eyes of articulated construction connected by hinge pins or bolts, the structure resembling the ordinary butt hinge of commerce, but possessing advantages and having uses which are incapable of being performed by ordinary hinges.

This new construction of hinge lends itself 65 for use as an overhead hinge in warehouses, factories and garages, in which uses, when the door is raised to its open position, it is adapted to form an awning or protection for the opening. It is, however, useful for exterior and communicating doors, garage doors, telephone booths, wardrobe lockers 70 and even on many kinds of furniture.

The invention will be best understood from a consideration of the following detailed description, taken in connection with the accompanying drawings forming part of this 75 specification, with the further understanding that while the drawings show a practical form of the invention, the latter is not confined to strict conformity with the showing of the drawings, but may be changed and so modified so long as such changes and modifications come within the scope of the appended claims.

Referring to the drawing:—

Fig. 1 represents an elevation of three narrow doors, arranged side by side, showing 85 two doors closed and one open, said doors being equipped with the hinge of the present invention.

Fig. 2 is a vertical section through the 90 open door, the door in its open position constituting an awning for the opening to protect it from rain and sun.

Fig. 3 is a front elevation showing a single wide door equipped with a plurality of 95 hinges of the present invention, weights and pulleys being shown in dotted lines for sustaining the door when raised.

Fig. 4 is a vertical section of the construction shown in Fig. 3, showing the door 100 closed.

Fig. 5 is a similar section of the construction illustrated in Fig. 3, with the door open and raised to its horizontal position.

Fig. 6 is an enlarged sectional view showing 105 the mounting of the hinge in its overhead position and illustrating in dotted lines the progressive movement of the door from the vertical position to the horizontal position.

Fig. 7 is an elevation on a small scale, showing the hinge applied to a door swinging in a horizontal plane.

Fig. 8 is a horizontal section taken on the line 8—8, Fig. 7.

Fig. 9 is a detail perspective view of one of the hinges detached.

Fig. 10 is an elevation of one of the arms of the hinge.

10 Fig. 11 is a longitudinal section of the same.

Fig. 12 is an elevation of the door plate.

Fig. 13 is a section of the same.

15 Fig. 14 is a longitudinal section of the jamb plate.

Fig. 15 is a transverse section illustrating the mounting of the jamb plate in the jamb strip.

Like reference characters indicate corresponding parts in the several figures of the drawing.

The hinge constituting the present invention is represented in detail in Figs. 9 to 14, inclusive, of the drawing.

25 It consists in part of two arms 10 and 11 made of flat metal of the same length, width and thickness. For general purposes, they are each made eight inches long, but the length is varied to suit the special conditions of service. Both ends of the arms are provided with spaced square notches, and the material is bent between the notches to form pintle eyes. In forming the eyes, the material is bent inwardly only so that the 30 eyes do not project beyond the outer face of the arms (see Fig. 11). By making the arms identical in shape and size, they may be stamped from the same dies.

40 The hinge includes a door plate and a jamb plate pivotally connected to the two arms. Both plates have substantially the same width as the arms. The door plate 12 is also made of flat metal, and is formed at its opposite ends with pintle eyes separated by notches in the same manner as the arms 10, 11 and is provided with screw holes for the reception of screws or bolts in fastening the door plate to the face of the door. The jamb plate 13 is bent transversely at an intermediate point of its length and thereby 45 made angular in form, and is provided with holes for screws or bolts in fastening the same on the jamb, and has its ends provided with pintle eyes separated by notches the same as the door plate and the two arms 10, 11. The jamb plate is larger than the door plate.

50 In assembling the parts of the hinge, the pintle eyes on the arms 10 and 11 fit in the notches which space the pintle eyes of the door and jamb plates while the pintle eyes of the said plates fit in the notches of said arms, in this way forming what is known as an articulated joint, being substantially 55 identical in principle of construction to the

ordinary butt-hinge. After the pintle eyes are thus assembled in matching relation, then pins or bolts are passed through the alined eyes so as to connect the four parts of the hinge together; that is to say, the 70 arms 10 and 11 each have one end connected in the manner described to the opposite ends of the door plate, while the other ends of said arms are connected to opposite ends of the jamb plate. In practice, the pins or 75 bolts 14, which connect one of the ends of the arms 10 and 11 to the door plate, and the pin or bolt 15 joining the other end of arm 11 to the jamb plate, have their ends riveted so that they cannot become detached, 80 but the pin or bolt 15^a connecting arm 10 to the end of the jamb plate is made removable for the purpose of permitting the hinge to be mounted in place. It will be obvious that by removing the bolt 15^a, the jamb plate 85 may be detached at one end and the arms of the hinge opened out allowing the door plate 12 to be fastened to the door, after which the jamb plate may be fastened in place, and when this is done, arm 10 may be 90 again connected to the free end of the jamb plate and held thereto by the bolt 15^a.

The hinge may be applied to a door swinging in a horizontal plane or in a vertical plane, and I have disclosed herein both 95 uses of the hinge. In making either application, the only change necessary in a standard door frame, is that a strip 16 be secured to the door frame to which the hinge is secured. This strip, which should be of 100 substantial construction, is grooved out at 16^a to receive one arm of the jamb plate. (See Figs. 6 and 15). The other arm fits flat against the outer exposed face of the strip, and both arms are secured in place by screws 105 or bolts, as shown. This arrangement brings the pivotal connections of the arms 10 and 11 to the jamb plate in different vertical planes, and at an angle to each other, the pivot connecting the arm 10 to the jamb plate being located at the inner end of the groove 16^a, and in the angle formed between said strip 16 and a part of the door frame. The other connection between the arm 11 and the jamb strip is extended out beyond 110 the strip 16 and is spaced therefrom. Precisely the same arrangement is followed, whether the door be hung to swing vertically or horizontally, as will be obvious upon a comparison between Fig. 6 and Fig. 8, the 115 latter representing the mounting of the hinge when the door swings horizontally.

Fig. 7 shows the improved hinge mounted on an ordinary door swinging in a horizontal plane, it being noted that the hinges are applied directly to the face of the door. In 120 small doors, two hinges are all that are necessary, each composed of the elements shown in Fig. 9; but in large doors, three or even four hinges may be found desirable for use, 125 130

and they may be made of greater dimensions than the size previously given.

In Figs. 1 to 5, inclusive, the hinge is shown in connection with doors which are 5 swung upwardly. In Fig. 1, a series of three doors are shown, each equipped with two hinges. Two of the doors are shown closed, and the other swung up into a horizontal position, in which position the door 10 serves as an awning or protection for the opening, which is normally closed by the door. In small doors, no counterweight is required to hold the doors in their open horizontal position when once raised, for the 15 reason that the arms of the hinge reach past the horizontal center of the door, but in the case of large doors, it is necessary to use a weight to counterbalance the same and to hold the doors in such position. I have 20 shown in Figs. 3, 4 and 5 how counterbalancing weights may be applied. In Fig. 3, a single large door is shown having a counterbalancing weight connected by ropes to the sides of the door, and moving in guides 25 of the framework. This door is shown provided with four hinges. Fig. 4 represents a sectional view showing the door closed, while Fig. 5 shows the door open in a horizontal position.

30 It will be understood that this construction of hinge possesses all the advantages of the hinge structure shown, described and claimed in my co-pending application Serial No. 346,455, but has the further advantage 35 that it involves less work to mount the same in place, the parts of the hinge being connected together as a unitary structure, and hence is more easily installed, and may be adapted to situations and conditions of use 40 which are not possible with the hinge of the aforesaid application.

The construction shown in Figs. 1 to 5, inclusive, illustrates the use of the hinge as an overhead hinge, for which use it is specially adapted. In churches and schools, it is customary to provide movable partitions to divide the auditorium into separate class rooms. At the end of the class exercises it is necessary to remove the partitions, which 50 takes considerable time and trouble, but with the hinge of the present invention, the partitions may be raised and carried up to the top of the frame in a horizontal plane, where they are out of the way and above the head 55 of any person in the room, and this may be accomplished with little effort and almost at a moment's notice.

This feature is also desirable for garage doors, for which purpose the door may be 60 made as three separate doors, as shown in Fig. 1, or as a single door, shown in Fig. 3. This construction is also adapted for warehouses and factory purposes, in which uses the fact that the door may be swung up into 65 a horizontal position where it forms an

awning for the opening, makes it peculiarly popular.

The construction may also be employed for short doors or sashes, or doors under stage fronts for schools.

The hinge of the present invention may be applied to ordinary horizontal swinging doors, as shown in Figs. 7 and 8 of the drawings, all the change necessary to be made being to remove the ordinary hinges and apply 75 the hinge of the present invention by inserting the strip 16 previously described.

The hinge is also useful for exterior and communicating doors, telephone booths, wardrobes, lockers, passenger coach doors, 80 and many kinds of furniture.

A specially desirable feature of this invention is that a door or other structure equipped with this hinge has no tendency to slam, but the door moves easily, noiselessly 85 and with little effort.

As hereinbefore stated, the pin or bolt 15^a connecting the arm 10 to the inner end of the jamb plate, is the only one of the four pins or bolts which is made removable. Now, 90 when the door is in the closed position (see Fig. 6), it will be noted that the edge of the door overhangs the pin or bolt, and it cannot then be removed. The pin or bolt can only be removed when the door is either 95 partly or entirely open. Of course, in structures which are not required to be locked against intrusion, all the pins or bolts may be made removable, which still further facilitates the installation of the hinge.

While the hinge is generally applied to doors or other closures, I do not wish to be limited to special applications of the hinge, for I have already indicated that it has a very wide range of usefulness. In the 105 claims, therefore, I shall use the terms "stationary member" and "movable member" in referring to the jamb or door frame and the door respectively, for in whatever relation or position or use the hinge may 110 be put, one part of the hinge must be secured to a movable member and the other part to a stationary member.

The operation of the door in swinging from a vertical to a horizontal position is 115 shown in dotted lines in Fig. 6 of the drawings. The same operation may be understood to take place when the door is mounted so as to swing in a horizontal plane, as in Figs. 7 and 8. It will be seen that in 120 no position of their movement are the arms 10 and 11 parallel to each other. When the door is mounted to swing in a horizontal plane, as in Figs. 7 and 8, the main portion 125 of the door vanishes within the compartment stall, booth or space closed by the door. The extent to which the door vanishes within the compartment, etc., may be regulated by increasing or decreasing the length of the arms 10, 11.

What is claimed is:—

1. A hinge comprising a pair of plates, and a pair of arms, the opposite ends of the arms being pivotally connected to one of the ends of each of the said plates, the plates and the arms being of the same width and the arms having the same length said arms being spaced from each other throughout their lengths. 5
10. 2. A hinge comprising a pair of plates and a pair of arms, the plates and the arms having substantially the same width and the arms having substantially the same length, opposite ends of the arms being pivotally connected to one of the ends of each of the said plates, one of said plates being bent transversely at an intermediate point of its length to dispose its ends at an angle to each other. 15
20. 3. A hinge comprising a pair of plates, and a pair of arms, the opposite ends of the arms being pivotally connected to one of the ends of each of the said plates, all of said elements being made of flat metal of the same width and certain of said pivotal connections being permanent and certain removable whereby said elements of the hinge constitute a unitary structure. 25
4. A hinge comprising a pair of plates, and a pair of arms, the opposite ends of the arms being pivotally connected to one of the ends of each of the said plates, one of said plates being longer than the other and bent transversely at an intermediate point of its length, the arms being of the same length and certain of said pivotal connections being fixed and certain detachable whereby the elements of said hinge are united to form a unitary structure. 30
40. 5. A hinge comprising a pair of plates, and a pair of arms, the opposite ends of the arms being pivotally connected to one of the ends of each of the said plates, the arms being made of flat metal straight from end to end and having the same length and width the pivotal connections between said elements being in the form of articulated joints, certain of which are fixed and certain are detachable forming a unitary structure. 45
50. 6. A hinge comprising a pair of plates, and a pair of arms, each plate and each arm having its respective ends formed with spaced pintle eyes, the eyes on the ends of the arms being constructed to articulate with the eyes on the ends of the plates, each arm being connected to both of the plates, and hinge pins or bolts passed through the meeting eyes to hold the arms and plates together as a unitary structure certain of the hinge pins or bolts being fixed and certain detachable. 55
65. 7. A hinge comprising a pair of plates, and a pair of arms, one of the plates being longer than the other and bent transversely between its ends, and the arms being of the same length, each plate and each arm having its respective ends formed with spaced pintle eyes, the eyes on the ends of the arms being constructed to articulate with the eyes on the ends of the plates, each arm being connected to both of the plates, and hinge pins or bolts passed through the meeting eyes to hold the arms and plates together as a unitary structure the hinge pins or bolts which connect the arms to the short plate and to one end of the longer plate being secured against removal. 70
80. 8. The combination with a stationary member having an inwardly projecting strip angular in cross section, of a movable member, and means for pivotally connecting the movable member to the stationary member, comprising an angular plate secured to said strip about the faces thereof, a plate secured to said movable member, and a pair of arms pivotally connected at their respective ends to the ends of the angular plate and the other plate, the movable member when in its closed position overlapping at one edge said strip and said angular plate. 85
90. 9. The combination with a stationary member having on its inner face a projecting strip angular in cross section, with one of its faces grooved, of a movable member, and means for pivotally connecting the movable member to the stationary member, comprising an angular plate having one of its arms fitted and secured in the groove of said strip, and its other arm secured to the other face thereof, a plate secured to the movable member, and a pair of arms pivotally connecting the ends of the angular plate to the other plate, said arms being of a substantially equal length, the door overlapping at one edge said strip and one of the arms of said angular plate when in its closed position. 95
100. 10. The combination with a door frame provided on its inner face with a strip angular in cross section, of a door, and means for pivotally connecting the door to the door frame, comprising an angular plate secured to two faces of said strip, a plate secured to the door, and a pair of arms of substantially equal length pivotally connecting the angular plate to the second-mentioned plate, the pivotal connections with the angular plate being so positioned that when the door is closed, one edge of the door fits within the door frame and overlaps the outer pivotal connection with said angular plate, whereby access to the said pivotal connection is obstructed. 110
11. The combination with a stationary member, of a movable member, and means for pivotally connecting the movable member to the stationary member, comprising a pair of arms of substantially the same length, a plate secured to the movable member, and an angular plate secured to the stationary member, the ends of the arms being 115
120. 125
- 130.

5 pivotally connected to the plate of the movable member and to the ends of the angular plate of the stationary member, all of said pivotal connections being located on the same side of the movable member when in its closed position and the pivotal connections with the angular plate being arranged at an angle to each other, and one of the pivotal connections with the stationary member 10 being overlapped by one edge of the movable member when closed.

12. The combination with a stationary member, of a movable member, and means for pivotally connecting the movable member to the stationary member, said means being applied to the movable member wholly within the edges thereof, and comprising a pair of arms, a plate secured to the movable member and an angular plate secured to the stationary member in angular relation to the movable member, the ends of the arms being pivotally connected to the respective ends of said plates, the pivotal connections of the arms with the plate of the stationary member 20 being located wholly at one side of the movable member when the latter is in its closed position and at an angle to each other and at different distances from the closed position of the movable member.

25 13. The combination with a door frame, a strip angular in cross section secured to the door frame at a point remote from its outer

edge, of a door, and means for pivotally connecting the door to said strip on the door frame, comprising an angular plate secured 35 to said strip in angular relation to the door, a plate secured to said door, and a pair of arms pivotally connected at their respective ends to the ends of said angular plate and the other plate, said door when in its closed 40 position overlapping at one edge one face of the angular plate and said angular strip and fitting within the door frame, and in its open position overlapping the other face of said plate and strip. 45

14. An overhead hinge for hanging doors wherein the door is caused to assume a substantially horizontal position when in its open position to serve as an awning or protection for the opening normally closed by 50 the door, the combination with a door frame, an angular plate secured to the door frame so that its ends are in different horizontal planes, a plate secured to the face of the door, and a pair of straight arms pivotally 55 connecting the ends of the angular plate to the ends of the door plate, whereby when the door is raised to a horizontal position one of the arms is substantially parallel with the door and the other arm is arranged at 60 an angle thereto.

In testimony, that I claim the foregoing as my own, I have hereto affixed my signature.

WILLIAM LEWIS EVANS, JR.
